UNITED STATES PATENT OFFICE.

WILLIAM CHALMERS FORBES, OF MELBOURNE, VICTORIA, AUSTRALIA.

DISTANCE AND COURSE RECORDER FOR SHIPS.

No. 881,068.

Specification of Letters Patent.

Patented March 3, 1908.

Application filed February 20, 1905. Serial No. 246,611.

To all whom it may concern:

Be it known that I, WILLIAM CHALMERS FORBES, a subject of the King of Great Britain, residing at S. S. *Edina*, Queen's Wharf, 5 Melbourne, in the State of Victoria, Australia, master mariner, have invented certain new and useful Improvements in and Relating to Distance and Course Recorders for Ships, of which the following is a specification.

10 This invention relates to that class of distance and course recorders wherein a rotator, mounted in the bottom of the ship is operated by the inrush of water as the ship travels, and is particularly applicable for rotating mechanism of the character set forth in my British Patent No. 25241 of 1902. One of the disadvantages of this class of recorder is that the inlet pipe protrudes permanently below the bottom of the ship and 20 cannot be removed except when in dry dock so that harbor dues are increased on account of the extra draft.

One of the objects of this invention is to remove this difficulty by making the inlet 25 pipe movable, so that it may be raised when entering harbors or passing over bars or sand banks; another is to provide a simple and reliable means for checking any inaccuracies in the steering.

30 Briefly stated, the removable tube in which the rotator is mounted is extended through an inverted U-shaped pipe and protrudes through the ship's bottom, the mouth of said tube being shaped to form a forwardly 35 opening inlet.

The motion of the rotator is transmitted by rods and cords etc., to a meter, and from the mechanism of same the rollers of the course recorder are set in motion and draw 40 the chart-ribbon along in touch with a recording pen, connected to the compass card, and by this means records not only the actual course traveled but the distance made good towards the ship's destination, thus 45 instituting a check against any inaccuracies in the steering.

It will be observed that the whole of the operating parts are so arranged in their casing that they may be readily withdrawn 50 therefrom, while valves are provided for closing the water inlet and outlet.

In order to facilitate a clear understanding of the invention the following drawings are appended viz,—Figure 1 a vertical section 55 with parts in elevation of the distance recorder mechanism. Fig. 2 an enlarged side

elevation of the course recorder mechanism. Fig. 3 a vertical section on line 111—111 of Fig. 2 with parts omitted. Figs. 4 and 5 represent detail sectional views of parts of 60 the mechanism.

According to this invention the rotator 1 is mounted within a tube 2 adapted to fit the inlet branch 3 of an inverted U-shaped pipe 4 riveted on the bottom 5 of the ship, said 65 tube being in communication with the U-shaped pipe by an opening 6. The tube 2 passes through a valve 7 in the inlet branch and the lower end thereof protrudes about two inches below the bottom of the ship and 70 is open at the front as shown and curved at the back as at 8 in order to direct the water up said tube and thereby impart a rotary motion to the rotator. The water then passes along the U-shaped pipe and is 75 discharged through the outlet branch 9 provided also with a valve 10, and having its mouth flush with the ship's bottom. This valve 10 is used for regulating the pressure 80 of the water in the U-shaped pipe. It will be understood that the opening and closing member or plug of the valve 7 will project through the tube 2, opposite openings of 85 suitable dimensions being provided in this tube to permit the valve to be opened or closed, and allow the said tube to perform its desired function. A copper or other suitable plate 11 is secured to the ship's bottom around the inlet and outlet pipes for the 90 purpose of preventing the growth of barnacles around same. The valves are operated by independent worm and wheel gearing 12 as shown in Fig. 1. When it is desired to stop the recorder the tube 2 is raised till it 95 clears the valve 7 and the latter is rotated, thus cutting off the admission of the water. By similarly closing the valve 10 of the outlet branch the water is prevented from rising in the casing of the mechanism while said 100 valve 10 is also used for regulating the passage of the water as before mentioned.

The shaft 120 of the rotator is mounted within a tapering plug 13 fitting the flared upper end 14 of the inlet branch of the pipe 4 and a casing 15, inclosing the whole mechanism is attached to said pipe. This casing is preferably of oval section and is provided on its inner lining with tapering guide sockets 16 into which fit lugs 17 depending vertically from a sleeve 18 attached to the 110 tapering plug 13. By this arrangement the inlet tube 2 is always lowered into its correct

position, and, furthermore, it is prevented from moving laterally. The rods and cords 19 which connect the rotator to the meter are provided with suitable means for adjusting their length as shown in Fig. 1.

The casing 15 has a cover 20 in the center of which is a cup 21, see enlarged detail view, Fig. 4, provided with a ring of balls 22 and the rod 19 connecting the rotator to the meter 24 passes freely through a hole in the cup and is provided with a comparatively large ball 23 which is adapted to rest on the balls in said cup. By this means a universal bearing is formed which will permit the ball 25 on the rod to gyrate in any direction.

The meter is mounted upon an arm 25 adjustably attached to a bracket 26 on the frame 27 of the course recorder.

The motion from the meter is conveyed by 20 beveled gearing 28 to the lower one 29 of a pair of friction rollers 29, 30 mounted one above the other in the frame, which revolve in unison by means of toothed wheels 31 in gear with each other and mounted on the 25 ends of their spindles 32. These spindles are loosely mounted in their bearings and the rollers are kept in contact by adjustable springs 33 bearing on the spindle of the upper roller.

30 At the upper end of the frame 27 is a loose roller 34 approximately in horizontal line with the upper friction roller 30, and about the center of the frame and beneath the loose roller is a detachable roller 35 upon 35 which the chart-ribbon 36 is wound. The tension of this roller is regulated by an adjustable spring operated lever 37 engaging one end of the spindle thereof, while the other is held in its bearing by a pivoted lever 40 38. The chart-ribbon 36 from the roller 35 passes around the loose roller 34, then horizontally over the upper friction roller 30 and between same and the lower one 29. The frame 27 which is of rectangular shape is adjustably connected by rods 39 to the bowl of the compass 40 which is either hung from an overhead frame 41 as shown in Fig. 2, or supported on a frame upon the floor or table of the chart room. Springs 42 may be advantageously employed as shown in order to 50 prevent the vibration of the ship affecting the recorder.

The recording pen 43 which is in touch with the chart-ribbon 36 is adjustably 55 mounted upon a light frame 44 passing vertically around the compass 40 and is adjustably attached to a pin 45 upon the compass card which extends up through a central hole in the glass face of the compass. The 60 frame 44 is provided with a sliding weight 46 by means of which the pen 43 may be truly balanced, and the frame 27 of the course recorder may also be weighted to counter-balance the weight of the meter.

65 The pen which I prefer to use is shown en-

larged by Fig. 5 and is one of the fountain class having a hollow tapering point with a fine thread 47 passing therethrough to the ink. When in operation the recorder is so adjusted that only the thread trails on the 70 chart-ribbon and hence there is no resistance offered to the compass which is an important feature of the invention.

During very rough weather a slight pendulous motion is set up in the course recorder 75 and in order to counteract same I attach to the frame a liquid cushion buffer comprising a number of vertical blades 48 secured upon a boss 49 and depending by a rod 50 from the frame 27 and suspended in a water 80 or other liquid tank 51 having an elongated neck 52 so that when the ship rolls the water acts as a liquid buffer against the blades and minimizes the vibration of the recording pen.

In order to prevent the compass becoming 85 sluggish I attach to the rotating rod of the meter a lateral arm 53 which is adapted to engage the lower end of a lever 54 pivoted as at 55 to the course recorder frame 27 and set at an incline so that its upper end normally 90 rests against the compass.

The inner tube is withdrawn when the valves are turned off and the pressure consequently reduced therein; by lifting the links out of their recesses by means of the 95 cords attached thereto. The spindle of the lower worm fits loosely within the hollow spindle of the upper worm so that each may be rotated independently by any suitable device. By this means the end of the lever 100 rises and falls continuously thus tapping the compass and keeping same "alive."

According to this invention as the vessel moves forward the motion of the rotator is communicated to the meter which as before 105 stated in turn unwinds the chart-ribbon so that the pen attached to the compass correctly traces on said chart the variations in the course of the ship.

Having now particularly described and 110 ascertained the nature of my said invention and in what manner the same is to be performed I declare that what I claim is:—

1. In a distance and course recorder or indicator for ships, the combination of an 115 inverted U-shaped pipe having one branch forming an inlet tube and the opposite branch an outlet, a tube slidably mounted in the said inlet branch and having the end thereof which is projectable below the ship's 120 bottom provided with an opening to the said outlet branch and also with the inlet opening presented in the direction of the ship's progress and with a scoop-shaped back, valves in the inlet and outlet branches, means for 125 lowering and raising the tube in the inlet branch, the said tube being movable above the valve in the inlet branch, recording mechanism, and a rotating operating device for the recording mechanism, the rotating 130

operating device being disposed in the said tube above the valve in the inlet branch.

2. In a distance and course recorder or indicator for ships, the combination of an inverted U-shaped pipe having one branch forming an inlet tube and the opposite branch an outlet, a tube slidably mounted in the inlet branch and having the end thereof which is projectable below the ship's bottom 10 provided with an opening to the said outlet branch and with an inlet opening presented in the direction of the ship's progress and with a scoop-shaped back, valves in the said inlet and outlet branches, means for lowering 15 and raising the tube in the inlet branch, the tube being movable above the valve in the inlet branch, recording mechanism, a rotating operating device also located in the tube above the valve and actuating the recording 20 mechanism, and means for independently operating the valves in the inlet and outlet branches.

3. In a recording or indicating mechanism for ships, means for delineating the course of 25 the ship, comprising a chart ribbon, a roller upon which the said ribbon is wound, a tensioning device for the said roller, and frictional rollers between which the chart has movement, in combination with a compass, a frame adjustable on the compass and carrying a meter and means for imparting motion to the chart ribbon, and a light frame 30 passing vertically around the compass and supported upon the latter, the said frame 35 which passes vertically around the compass

carrying a marking instrument consisting of a receptacle for marking fluid and a thread, the end of the thread protruding from the receptacle and adapted to trail upon the chart ribbon.

4. In a recording or indicating mechanism for ships, means for delineating the course of the ship, comprising a chart ribbon, a roller upon which the said ribbon is wound, a tensioning device for the roller, and frictional 40 rollers between which the chart has movement, in combination with a compass, having a pin, a frame adjustable on the compass and carrying a meter and means for imparting motion to the chart ribbon, the said 45 frame being provided with a lever which is pivoted thereto and has its upper end in operative relation to the compass to tap the latter and keep it alive, and a light frame 50 passing vertically around the compass and supported by the pin of said compass and carrying a marking instrument consisting of a receptacle containing a marking fluid and a thread, the end of the thread protruding from the receptacle and adapted to trail 55 upon the chart ribbon, the meter being provided with a lateral arm which engages the lever.

In testimony whereof I have hereunto set my hand in presence of two subscribing 60 witnesses.

WILLIAM CHALMERS FORBES.
